Specification for Design.

Patented Mar. 29, 1921.

Application filed July 3, 1919. Serial No. 308,679. Term of patent 14 years.

To all whom it may concern:

Be it known that we, DANIEL B. MCKINNEY and JOSEPH DUSCH, citizens of the United States of America, and residents of Wheeling, county of Ohio, and State of West Virginia, have invented a new, original, and ornamental Design for a Burial-Vault, of which the following is a specification, reference being had to the accompanying drawings, in which—

Fig. 2 is a side view of the same, and—

Fig. 3 is an end view of the same.

We claim:

The ornamental design for a burial vault, as shown.

In testimony whereof we hereunto affix our signatures in the presence of two subscribing witnesses.

DANIEL B. MCKINNEY.
JOSEPH DUSCH.
